(57) CLAIM

The ornamental design for a grill, as shown and described.

DESCRIPTION

FIG. 1 is a perspective view of a grill showing my new design;

FIG. 2 is a front side view thereof;

FIG. 3 is a back side view thereof;

FIG. 4 is a left side view thereof;

FIG. 5 is a right side view thereof;

FIG. 6 is a top plan view thereof;

FIG. 7 is another perspective view of grill; and,

FIG. 8 is the perspective view of grill opening the upper cover.

The broken lines in the drawings depict portions of the grill that form no part of the claimed design.
